J. REID

METHOD OF PRODUCING ADVERTISING SIGNS IN THE AIR AND PRODUCT

Filed May 5, 1920

Inventor:
John Reid.
by his Attorneys
Brown & Brown.

UNITED STATES PATENT OFFICE.

JOHN REID, OF GLASGOW, SCOTLAND, ASSIGNOR TO ALFRED ERNEST WHITE, OF LONDON, ENGLAND.

METHOD OF PRODUCING ADVERTISING SIGNS IN THE AIR AND PRODUCT.

Application filed May 5, 1920, Serial No. 379,187, and in Great Britain May 7, 1919.

This invention has reference to a new and improved method or system of forming and producing announcements, advertisements and the like in the air from aeroplanes, air-ships, and such like flying machines.

The attached drawing illustrates diagrammatically the method of making advertisements, signs and the like according to my invention.

10 According to my improvements I release the exhaust or other escape from the engine or smoke, gas, vapour or other chemical from a container, accumulator and the like in an aeroplane, and I then maneuver the 15 machine while emitting the exhaust or liberating the gas vapor or other chemical or like fluid or liquid to give the configuration of a letter, figure, and the like and I may then go on continuously maneuvering the 20 aeroplane to produce the further letters or configurations; or I may shut off the exhaust from the engine or fluid from a container and pass through the air and liberate the fluid in space at any altitude and maneuver 25 the machine to produce the second letter configuration or their equivalent.

With reference to the drawings, *a* represents the flying machine, and *b* the exhaust from the engine or gas or vapor from a separate container which marks the path traversed by the aeroplane.

In applying same to produce announcements, advertisements and the like such for example as the words "Peace or Pears" the 35 exhaust or container would be opened to liberate the fluid at one part, and the machine maneuvered to produce the first letter and then the exhaust or container be shut off and the fluid liberated to produce the second 40 letter, and so on for the remaining letters;

or the letters or their equivalent can be produced in sequence from the first or a continuous liberation of exhaust from the engine or fluid from the container.

In night time the fluid used may be of 45 phosphorescent or of other luminous substance or fluid, and manipulations take place to give the effect required.

What I claim is:—

1. In a system of advertising, the method 50 of establishing designs in the air, which consists in maneuvering an aeroplane, giving off a visible substance in such manner that the path of said aeroplane, as defined by said substance, forms the desired design. 55

2. The method of forming designs of predetermined form in air, which consists in maneuvering a self propelled machine emitting a visible gas in the air in such manner that the path thereof defines the desired de- 60 sign.

3. The method of producing advertising signs comprising alphabetical letters, words, and designs, suspended in the air, which consists in the production or storing 65 in an aeroplane of a smoke-like material of persistent visibility and maneuvering said plane in paths corresponding with the form of the desired sign, whilst emitting a trail of said smoke-like material at such height and 70 in such volume that an advertisement is formed readable with the naked eye by persons distant on the earth.

4. As an aeronautic product, an advertising sign comprising a combination of alphabetical letters, words, or a design, composed 75 of smoke suspended in the air and in form readable with the naked eye by persons distant on the earth.

JOHN REID.

Patented Mar. 15, 1927.

UNITED STATES PATENT OFFICE.

JOHN REID, OF GLASGOW, SCOTLAND, ASSIGNEE TO ALFRED ERNEST WHITE, OF LONDON, ENGLAND.

METHOD OF PRODUCING ADVERTISING SIGNS IN THE AIR AND PRODUCT.

Application filed May 5, 1920, Serial No. 379,187, and in Great Britain May 7, 1919.

This invention has reference to a new and improved method or system of forming and producing announcements, advertisements and the like in the air from aeroplanes, air-ships, and such like flying machines.

The attached drawing illustrates diagrammatically the method of making advertisements, signs and the like according to my invention.

According to my improvements I release the exhaust or other escape from the engine or smoke, gas, vapour or other chemical from a container, accumulator and the like in an aeroplane, and I then maneuver the machine while emitting the exhaust or liberating the gas vapor or other chemical or like fluid or liquid to give the configuration of a letter, figure, and the like and I may then go on continuously maneuvering the aeroplane to produce the further letters or configurations; or I may shut off the exhaust from the engine or fluid from a container and pass through the air and liberate the fluid in space at any altitude and maneuver the machine to produce the second letter configuration or their equivalent.

With reference to the drawings, *a* represents the flying machine, and *b* the exhaust from the engine or gas or vapor from a separate container which marks the path traversed by the aeroplane.

In applying same to produce announcements, advertisements and the like such for example as the words "Peace or Pears" the exhaust or container would be opened to liberate the fluid at one part, and the machine maneuvered to produce the first letter and then the exhaust or container be shut off and the fluid liberated to produce the second letter, and so on for the remaining letters;

or the letters or their equivalent can be produced in sequence from the first or a continuous liberation of exhaust from the engine or fluid from the container.

In night time the fluid used may be of phosphorescent or of other luminous substance or fluid, and manipulations take place to give the effect required.

What I claim is:—

1. In a system of advertising, the method of establishing designs in the air, which consists in maneuvering an aeroplane, giving off a visible substance in such manner that the path of said aeroplane, as defined by said substance, forms the desired design. 50

2. The method of forming designs of predetermined form in air, which consists in maneuvering a self propelled machine emitting a visible gas in the air in such manner that the path thereof defines the desired design. 60

3. The method of producing advertising signs comprising alphabetical letters, words, and designs, suspended in the air, which consists in the production or storing in an aeroplane of a smoke-like material of persistent visibility and maneuvering said plane in paths corresponding with the form of the desired sign, whilst emitting a trail of said smoke-like material at such height and in such volume that an advertisement is formed readable with the naked eye by persons distant on the earth. 65

4. As an aeronautic product, an advertising sign comprising a combination of alphabetical letters, words, or a design, composed of smoke suspended in the air and in form readable with the naked eye by persons distant on the earth. 75

JOHN REID.

DISCLAIMER

1,621,482.—John Reid, Glasgow, Scotland. METHOD OF PRODUCING ADVERTISING SIGNS IN THE AIR AND PRODUCT. Patent dated March 15, 1927. Disclaimer filed September 22, 1937, by the assignee, John Clifford Savage.

Hereby enters this disclaimer to that part of the claim in said specification which is in the following words, to wit: "I may then go on continuously maneuvering the aeroplane to produce the further letters or configurations; or".
